CLAIM

I claim the ornamental design for a water ball, as shown and described.

DESCRIPTION

FIG. 1 is a first perspective view of a water ball in a closed state in accordance with my new design, wherein the water ball can hold water therein when the water ball is played; FIG. 2 is a second perspective view of the water ball of FIG. 1;

FIG. 3 is a front view of the water ball of FIG. 1;

FIG. 4 is a rear view of the water ball of FIG. 1;

FIG. 5 is a left side view of the water ball of FIG. 1;

FIG. 6 is a right side view of the water ball of FIG. 1;

FIG. 7 is a top view of the water ball of FIG. 1;

FIG. 8 is a bottom view of the water ball of FIG. 1; and,

FIG. 9 is a perspective view of the water ball of FIG. 1 in an open state.

The broken lines shown in the drawings depict portions of the water ball that form no part of the claimed design.
